UNITED STATES PATENT OFFICE.

HUBERT W. MORGAN, OF LAKEWOOD, OHIO.

PROCESS FOR MANUFACTURING SYNTHETIC LEATHER.

No Drawing.

Application filed October 30, 1919. Serial No. 334,593.

To all whom it may concern:

Be it known that I, HUBERT W. MORGAN, a citizen of the United States, and resident of Lakewood, in the county of Cuyahoga and State of Ohio, have invented certain new and useful Improvements in Processes for Manufacturing Synthetic Leather, of which I hereby declare the following to be a full, clear, and exact description, such as 10 will enable others skilled in the art to which it appertains to make and use the same.

The objects of the invention are to provide an improved process or method of producing an efficient and useful material having all 15 the valuable qualities of natural leather, including great tensile strength, softness and flexibility and superior wearing qualities with the added advantage that it is waterproof and all of these qualities are controllable to adapt the material to a large variety 20 of commercial uses.

By means of this process a material is produced having a controllable amount of flexibility and tensile strength which will out- 25 wear natural leather and is capable of being employed in the mechanical arts, and for universal use in every situation in which leather or its several substitutes can be employed, and at very much less initial cost for 30 materials and labor.

Further advantages are found in the economical use of scraps cut or trimmed from the improved material which can be re-treated and incorporated into sheets of 35 equally good material for further use.

This cannot be accomplished with natural leather or canvas coated or other coated substances of leather.

By means of the process, a homogeneous 40 product is obtained which can be rolled into sheets of any desired thickness and by regulating the duration of time of the different portions of the treatment, the toughness, amount of tensile strength and the softness 45 and flexibility of the product, and the fineness and evenness of texture, can be positively controlled.

The material can also be washed or cleaned and its surface grained, embossed 50 or finished in the same manner as leather, also when colored the entire body of the material is permeated throughout with the color, so that the appearance when worn, is superior to that of leather.

55 The various steps of the process which include, physical, chemical, and mechanical

operations, are hereinafter more fully described in their proper order of succession from the collection of the crude material until the product is ready for commercial 60 use.

The materials employed are fibrous materials of any sort such as wood fiber, in a fine condition as saw dust or wood flour, old rags or rope, straw, grass, hemp, jute, etc. 65 From these materials a pulp is prepared by digesting them in the natural state, or by previously shredding or powdering them to bring them into a uniform finely divided condition. 70

Since the tensile strength of the completed material does not wholly depend on the length of the fiber, it is more easily brought into a product having a fine and even texture if the crude materials are previously 75 shredded to a uniform amount of fineness. This also makes the materials easier to handle.

Before going through the digesting process, all oil and grease are removed from the 80 material by means of a hot bath in an alkaline solution of caustic soda. This bath when continued will also soften and partially dissolve the fibers, the duration of the period of its use depending upon the 85 strength of the solution employed. After having received this bath, it is washed to remove the traces of soda, and is then subjected to a further digesting process in a bath of weak acetic acid, or combination of 90 acids or solvents, which has the effect of reducing some of the fibrous materials to an amorphous cellulose condition and partially digesting others, until the remaining fibrous material will not exceed a predeter- 95 mined percentage of the whole mass, according to the ultimate tensile strength and fineness and quality of the product desired, and is also commensurate with the amount of toughness, softness and flexibility desired, 100 since the softness would be lost if the whole mass was converted into cellulose.

By means of this step, the mass is reduced to a soft plastic condition. The acid treatment is of short duration and after the material has arrived at the plastic and dough-like condition, any desired binding material, such as lac, or varnish gum, or any kind of gummy material is dissolved in a solvent such as bi-sulphide of carbon, or one of the 110 petrols, such as gasoline or benzole, and is added in a proportion determined by the

amount of flexibility desired in the finished product, and thoroughly incorporated with the mass by kneading, pressing and rubbing under mechanical pressure in any suitable device until the binder and mass are completely unified; also any coloring pigment can be introduced at the same time in the same manner.

The kneading, pressing and rubbing actions have a pronounced physical effect in unifying and amalgamating the mass.

The next stage of the treatment consists in exposing the mass to the air, or air and sun, which has the effect of tempering or setting the mass, and evaporating the solvents from the surface, and leaving it in a condition to be mechanically treated to produce the flexible sheets adapted for commercial use.

20 This is accomplished by passing the plastic material through a succession of moderately heated rolls or through rolls in a chamber in a perfectly dry or artificially dried atmosphere, the object being to flatten and elongate the mass and reduce it to the form of sheets, which can be cut into sizes suitable for commercial use, and also to submit it to a further kneading pressure, which effects a further amalgamation and unification of the mass, which produces an improved fineness and evenness of texture throughout, the physical action of the rollers solidifying the mass in which the fibrous condition gradually disappears.

35 If this treatment by rolling pressure is carried too far, the material will harden and lose flexibility, and the period of rolling is determined by the thickness of the material desired, and the quality of the finished product.

After rolling, and before curing, any desired finish of surface can be given to the sheets, such as graining, embossing or other finish.

45 The final stage comprises exposing the sheets in a heated room to a current of air until they are perfectly cured; the time of the exposure depending upon the amount of cellulose in the structure and the thickness of the material.

The strength of the material increases constantly during the curing process and for months afterwards, and the quality will not deteriorate when the sheets have been manufactured, and the manufactured articles have been put into use, or when the sheets are stored and the materials standing idle because there is no animal matter in the composition, thus making it superior in durability to leather or imitations thereof.

The process is also of short duration and is much less expensive in time and labor than the innumerable processes to which leather must be subjected in soaking the skins,

tanning, tawing, softening, finishing and treating for its several uses.

Having described the invention, what I claim as new and desire to secure by Letter Patent is:—

1. The hereinbefore described process of manufacturing a leatherlike material consisting in collecting a mass of fibrous material, treating the same to a bath of softening solution, and next to a bath of acetic acid, permitting the same to partially set, and then mechanically manipulating to compress and solidify the same, and then curing the mass.

2. The hereinbefore described process of reducing a mass of fibers to a partially amorphous cellulose and plastic condition, said mass containing unreduced fibers, consisting in, treating said mass of fibers in an alkaline solution to soften and partially dissolve the same, next treating the mass in a bath of weak acetic acid for a limited period of time, determined by the amount of softness, tenacity and fineness of substance of the product, desired, and finally curing the same.

3. The hereinbefore described process of manufacturing a flexible product having the characteristics of leather, consisting in, first, reducing the mass of fibers to an amorphous cellulose and plastic body, having partially dissolved fibres therein, by first treating the fibers in a bath of caustic solution to remove all oil or grease therefrom, and to soften and partially dissolve the same, next removing the caustic solution therefrom, and next treating the fibers in a bath of weak sylvic acid until a proportion of the fibers are reduced to amorphous cellulose, the proportion of unreduced fibers remaining being determined by the softness, flexibility and fineness of quality desired in the product and finally curing the same.

4. A process for manufacturing a leather material including, first, providing a mass of previously softened fibrous material, immersing the mass in weak acetic acid until a predetermined percentage of the fibrous material has been converted into an amorphous body thus forming a plastic, dough-like mass, incorporating a binder therein, allowing the mass to partially set and mechanically compressing and kneading the mass to flatten and solidify the same to give fineness and evenness of texture thereto and finally curing the same by exposing it to circulation of air in a heated room.

In testimony whereof, I hereunto set my hand this 13th day of October, 1919.

HUBERT W. MORGAN.

In presence of—

S. W. SANGSTER,
W. M. MONROE.
